Primary Examiner — Ruth McInroy(74) *Attorney, Agent, or Firm* — Rodgers & Rodgers(57) **CLAIM**

The ornamental design for a universal barbecue grill heat distribution plate, as shown and described.

DESCRIPTION

FIG. 1 is a perspective view of a universal barbecue grill heat distribution plate showing my new design;

FIG. 2 is a top plan view thereof;

FIG. 3 is a front elevational view thereof, the rear being a mirror image thereof;

FIG. 4 is a bottom plan view thereof; and,

FIG. 5 is a left-side elevation view thereof, the right side being identical.

The dotted lines are for illustrative purposes only and form no part of the claimed design.
